2,496,378

CAVITY RESONATOR DEVICE FOR
ULTRA-SHORT WAVES

Frederik Coeterier, Eindhoven, Netherlands, assignor, by mesne assignments, to Hartford National Bank and Trust Company, Hartford, Conn., as trustee

Application April 24, 1946, Serial No. 664,498
In the Netherlands June 27, 1942

Section 1, Public Law 690, August 8, 1946
Patent expires June 27, 1962

12 Claims. (Cl. 315—6)

1

This invention relates to a resonator, particularly a cavity resonator, and a device comprising such a cavity resonator.

The term cavity resonator is to be understood here and hereinafter to mean an oscillatory circuit for ultra-short waves constituted as a cavity resonator in which a concentrated inductance and capacity are missing and the dimensions of which are hence of the order of magnitude of the wavelength of the fundamental frequency (smallest natural frequency). As set out more fully for example in Philips' Technisch Tijdschrift, July 1941, pages 222, 223 the said resonators are among the non-quasi-stationary systems.

The wall of a cavity resonator constitutes a body closed on all sides except, as is well-known, for the apertures which have to be formed in the wall, for example for the wired electrical connection to the inside of the wall or for the introduction of coupling loops.

In addition, devices for ultra-short waves are known in which use is made of a discharge tube which is provided with means for the generation of an electron beam and in which the electron beam passes through the bore of a cavity constructed as a cavity resonator.

The apertures formed in the wall of the resonator, particularly if their dimensions are no longer small compared with the wavelength, bring about considerable lowering of the quality of the cavity resonator.

The invention has for its object to provide means for limiting this loss in quality while conserving the accessibility of the aperture with a cavity resonator.

According to the invention, for this purpose the path followed by a loss current emerging over the edge of the aperture has connected in series therewith a secondary cavity resonator provided with a bore and preferably constructed as a cavity resonator which has a natural frequency that corresponds with a natural frequency of the primary resonator and which is so arranged that the aperture is in line with the bore.

The measure according to the invention has the effect of introducing a high resistance, that is the resonance resistance of the secondary resonator, into the loss current path, with the result that the loss current is limited.

In order that the invention may be clearly understood and readily carried into effect it will now be described more fully with reference to the accompanying drawing, in which

Fig. 1 is a known cavity resonator.

2

Fig. 2 shows a cavity resonator according to the invention having flat secondary cavity resonators.

Fig. 3 shows a cavity resonator according to the invention comprising secondary cavity resonators each of which is constituted by two concentric conductors.

Fig. 4 shows a section of a device according to the invention comprising a discharge tube.

10 Referring to Fig. 1 a cavity resonator 1 which is rotation-symmetrical with respect to the axis 2 has apertures 4, 4' formed in its wall 3. On excitation of the cavity resonator for example by means of a loop-like conductor 5, the edge of the aperture 4, which edge is located in a potential antinode, will be at a high-frequency voltage relatively to the surroundings. Due to this, other parts of the external surface of the cavity resonator will also be at high-frequency voltage relatively to the surroundings and, since the outer wall, as denoted in the figure by 1 and 1', must be regarded as earthed by capacitative agency, a considerable loss current ensues. This loss current, which emerges over the edge 6 of the aperture, 20 follows the path shown in dotted lines in the figure and is responsible for considerable lowering in quality of the cavity resonator.

According to the invention, this loss of quality is limited by the use of secondary cavity resonators, 8, 8' arranged in the manner shown in Fig. 2 so that the said loss current is conducted via one of these secondary resonators. The latter are bored at 4, 9 and 4', 9' so that the apertures 4 and 4' of the primary cavity resonator continue accessible. The resonance resistance occurring between the ends 4 and 9 of the secondary cavity resonator 8 is thus inserted in the loss current. In the case of loss-free construction of the cavity resonator 8 this 30 introduces substantial suppression of the loss current since due to the potential distribution now occurring in the loss current path the edges 10 and 10' of the secondary cavity resonators 8 and 8' respectively and thus the outside of all cavity resonators will be substantially at earth potential and hence the capacity (1, 1') will have no longer any harmful effect as regards the surrounding.

If, as hitherto taken for granted, the primary cavity resonator is not excited in its fundamental frequency but in one of the higher natural frequencies, the secondary cavity resonators must obviously be tuned to this higher natural frequency. According to circumstances, it may be advantageous to cause the fundamental frequency 40 of the secondary cavity resonator to correspond

with a higher natural frequency of the primary cavity resonator since the required space is thus limited. For the purpose of limiting the accuracy requirements as to the dimensions of the cavity resonators from a mechanical point of view and also for compensating circuit capacities or the like it is desirable that use should be made of means for adjusting the natural frequencies of the secondary cavity resonators, for example a member formed of insulating material or a conductor may for this purpose be arranged in the cavity resonator concerned.

In the form of construction shown in Fig. 2 radiation losses occur through the apertures 9, 9' of the secondary cavity resonators 8, 8' as originally with the cavity resonator 1 through the apertures 4, 4'. The said radiation losses can be reduced by constituting the secondary cavity resonators, as shown in Fig. 3, by two concentric hollow conductors 11, 12 and 11', 12' respectively united at corresponding ends, the internal conductors 12, 12' comprising an interruption 13, 13' immediately adjacent the apertures 4, 4'.

If desired, adjoining cavity resonators may in this case have a common wall part, as in Fig. 2.

The invention may be used with particular advantage with devices for ultra-short waves in which use is made of a discharge tube comprising means for generating an electron beam and the electron beam traverses the bore of a cavity resonator, either for the purpose of modulating the speed of the electron beam or to derive energy from the intensity-modulated beam. In such devices it is often desirable or even necessary that the bore of the cavity resonator should be made comparatively large, it being so large that particularly with very short waves the dimensions of the apertures made in the cavity resonator are no longer small compared with the operating wavelength, this entailing great losses.

Fig. 4 shows such a device for generating ultra-short waves to which the invention is applied.

A discharge tube 14 has arranged in it on the one side an electrode system 15 for generating the electron beam and on the other a collector electrode 16.

In between are arranged two mutually coupled primary cavity resonators 17 and 18 respectively. The cavity resonator 17 serves for the velocity modulation of the electron beam. In the space intermediate the two cavity resonators this velocity modulation is converted into an intensity modulation so that the cavity resonator 18 permits of deriving energy from the beam.

For the purpose of improving the quality of the primary cavity resonators 17 and 18 provision is made of secondary cavity resonators 19, 19' and 20, 20' serving solely for this purpose and constituted essentially, by two concentric, hollow conductors whose interrupted internal conductors are aligned with the bores of the primary cavity resonators so that the electron beam can pass without any obstruction. If desired, the secondary cavity resonator may be arranged, as distinguished from the embodiment illustrated, entirely outside the surrounding envelope of the discharge tube.

In this construction, the cavity resonators 17 and 19' are not arranged in direct contact with each other but at a small distance and are interconnected by a metal tube piece 21 in order that it may be possible for a concentration coil 22 to be arranged in the space thus obtained between the said cavity resonators.

In the embodiments shown the primary cavity

resonator has always a bore at the area of a potential antinode. Obviously, however, the invention may also be applied if the primary cavity has only formed in it a single aperture which consequently does not constitute a bore or else one or more apertures not arranged at the area of a potential antinode and also in the case of the primary cavity resonator having for example a concentrated capacity.

Lastly, the secondary cavity resonator may have a concentrated capacity and/or inductance in order to limit the required space in so far as is permitted by the quality improvement aimed at of the primary hollow space resonator.

It is to be understood that the invention is not limited to those specific embodiments herein described, but that various modifications will occur to those skilled in the art without departing from the spirit and the scope of the invention.

I claim:

1. A cavity resonator system comprising a first cavity resonator and a second cavity resonator having a resonant frequency corresponding to the resonant frequency of said first resonator, said resonators having contiguous wall portions provided with coincident apertures, the diameter of said apertures being less than the axial dimension of said first cavity resonator, and said second resonator being provided in another wall portion thereof with a second aperture in line with said first apertures.

2. A cavity resonator system comprising a primary cavity resonator having a wall portion provided with an aperture whose diameter is less than the axial dimension of said primary resonator, and means to reduce electrical losses occurring at said aperture, said means comprising a secondary cavity resonator having a resonant frequency corresponding to the resonant frequency of said primary resonator, a wall portion contiguous to said first wall portion and provided with an aperture coincident with said aperture of said first wall portion, and a second wall portion provided with an aperture in line with the apertures in said contiguous wall portions.

3. A cavity resonator system comprising a primary cavity resonator having a wall portion provided with an aperture whose diameter is smaller than the axial dimension of said primary resonator, and means to reduce electrical losses occurring at said aperture, said means comprising a secondary cavity resonator having a resonant frequency corresponding to the resonant frequency of said primary resonator, a wall portion including said aperture in common with said primary resonator, and a second wall portion provided with an aperture in line with said first aperture.

4. A cavity resonator system comprising a primary cavity resonator having spaced wall portions each provided with an aperture, whose diameter is small with respect to the spacing between said wall portions, and means to reduce electrical losses occurring at said apertures, said means comprising a first secondary cavity resonator having a wall portion contiguous to one of said wall portions of said primary resonator, and provided with an aperture coincident with the aperture of said wall portion of said primary resonator and a second wall portion provided with an aperture in line with the apertures in said contiguous wall portions, and a second secondary cavity resonator having a wall portion contiguous to the other of said wall portions of said primary resonator and provided with an aperture coin-

cident with the aperture of said other of said wall portions of said primary resonator and a second wall portion provided with an aperture in line with the apertures in said second contiguous wall portions, said first and said second secondary resonators having a resonant frequency corresponding to the resonant frequency of said primary resonator.

5. A cavity resonator system comprising a primary cavity resonator having spaced wall portions each provided with an aperture having a diameter which is small with respect to the spacing between said wall portions, and two secondary cavity resonators each positioned adjacent to one of said wall portions, said secondary resonators each having a first wall portion contiguous to said wall portions of said primary resonator and provided with an aperture coincident with said aperture of said contiguous wall portion and a second wall portion provided with an aperture in line with said apertures of said contiguous wall portions, each of said secondary resonators having a resonant frequency corresponding to the resonant frequency of said primary resonator.

6. A cavity resonator system comprising a primary cavity resonator having spaced wall portions each provided with an aperture having a diameter which is small with respect to the spacing between said wall portions, and two secondary cavity resonators each positioned adjacent to one of said wall portions, said secondary resonators each having a first wall portion contiguous to said wall portions of said primary resonator and provided with an aperture coincident with said aperture of said contiguous wall portions and a second wall portion comprising a tubular member extending within said second secondary resonator, said tubular member being provided with a bore an axis of which is coincident with the axis of the apertures of said contiguous wall portions, and said secondary resonators having a resonant frequency corresponding to the resonant frequency of said primary resonator.

7. A cavity resonator system comprising a primary cavity resonator having spaced wall portions each provided with an aperture having a diameter which is small with respect to the spacing between said wall portions, and two secondary cavity resonators each positioned adjacent to one of said wall portions each of said secondary resonators having a first wall portion contiguous to one of said wall portions of said primary resonator and provided with an aperture coincident with said aperture of said contiguous wall portions and a second wall portion, said second wall portion comprising a tubular member extending within said second secondary resonator to an antinode potential region and provided with a bore an axis of which is coincident with the axis of the apertures of said contiguous wall portions, said secondary resonators having a resonant frequency corresponding to the resonant frequency of said primary resonator.

8. A cavity resonator system comprising a primary cavity resonator having spaced wall portions each provided with an aperture having a diameter which is small with respect to the spacing between said wall portions, and two secondary cavity resonators each having a wall portion including said aperture in common with said primary resonator, each of said secondary resonators comprising two concentric conductors the axes of which are coincident with the axis of said apertures of said common wall portions, and means interconnecting said conductors at the

ends thereof remote from said common wall portions said secondary resonators having a resonant frequency corresponding to the resonant frequency of said primary resonator.

- 5 9. A cavity resonator system comprising a primary cavity resonator having spaced wall portions each provided with an aperture having a diameter which is small with respect to the spacing between said wall portions, and two secondary cavity resonators each having a wall portion including said aperture in common with said resonator, each of said secondary resonators comprising two concentric conductors, the axes of which are coincident with the axis of said apertures of said common wall portions, and means interconnecting said conductors at the ends thereof remote from said common wall portions, the inner conductor of said conductors terminating at an antinode potential region in the secondary resonator, said secondary resonators having a resonant frequency corresponding to the resonant frequency of said primary resonator.
- 10 10. A cavity resonator system comprising a primary resonator having spaced wall portions each provided with an aperture having a diameter which is small with respect to the spacing between said wall portions, and two secondary cavity resonators each having a wall portion including said aperture in common with said primary resonator, each of said secondary resonators comprising two concentric cylindrical conductors the axes of which are coincident with the axis of said apertures of said common wall portions, and a disc member interconnecting said conductors at the ends thereof remote from the common wall portion, said secondary resonators having a resonant frequency corresponding to the resonant frequency of said primary resonator.
- 15 11. A cavity resonator system comprising a first group of cavity resonator elements, a second group of cavity resonator elements spaced from and axially aligned with said first group, each of said groups comprising primary cavity resonator having spaced wall portions each provided with an aperture, and a first secondary cavity resonator each having a wall portion including said aperture in common with said primary resonator and comprising two concentric tubular conductors the axes of each are coincident with an axis of said aperture of said common wall portions and means interconnecting said conductors at the ends thereof remote from said common wall portions, said first group of cavity resonators further comprising a concentrator solenoid positioned adjacent to said primary resonator, and a second secondary cavity resonator comprising a wall portion positioned adjacent to said solenoid and provided with an aperture axially aligned with the apertures of the primary cavity resonator, said second secondary resonator further comprising two concentric tubular conductors the axes of which are coincident with the axis of said apertures of said common wall portions and means interconnecting said conductors at the ends thereof remote from said common wall portions, a tubular conducting member interposed between said primary resonator and said second secondary resonator and through said solenoid said second group of cavity resonators comprising a second secondary cavity resonator comprising two concentric tubular conductors the axes of which are coincident with the axis of said aperture of said common wall portions and means interconnecting said conductors at the ends thereof remote from said common

wall portions, the inner conductor of said secondary cavity resonators extending within the resonator to an antinode potential region, means electrically coupling the primary cavity resonators of each of said groups, the resonant frequency of the resonator of said first group corresponding to the resonant frequency of the resonator of said second group, and the resonant frequency of said secondary resonators of each of said groups corresponding to the resonant frequency of the primary resonator of said groups.

12. A cavity resonator system comprising a first group of cavity resonator elements, a second group of cavity resonator elements spaced from and axially aligned with said first group, each of said groups comprising primary cavity resonator having spaced wall portions each provided with an aperture and a first secondary cavity resonator each having a wall portion including said aperture in common with said primary resonator and comprising two concentric tubular conductors the axes of each are coincident with the axis of said aperture of said common wall portions and means interconnecting said conductors at the ends thereof remote from said common wall portions, said first group of cavity resonators further comprising a concentrator solenoid positioned adjacent to said primary resonator, and a second secondary cavity resonator comprising a wall portion positioned adjacent to said solenoid and provided with an aperture axially aligned with the apertures of the primary cavity resonator, said second secondary resonator further comprising two concentric tubular conductors the axes of which are coincident with the axis of said apertures of said common wall portions and means interconnecting said conductors at the ends thereof remote from said common wall portions, a tubular conducting member interposed between said primary resonator and said second secondary resonator and through said solenoid, said second group of cavity resonators comprising a second

secondary cavity resonator comprising two concentric tubular conductors the axes of which are coincident with the axis of said aperture of said common wall portions and means interconnecting said conductors at the ends thereof remote from said common wall portions, the inner conductor of said secondary cavity resonators extending within the resonator to an antinode potential region, means electrically coupling the primary cavity resonators of each of said groups, the resonant frequency of the resonator of said first group corresponding to the resonant frequency of the resonator of said second group, the resonant frequency of said secondary resonators of each of said groups corresponding to the resonant frequency of the resonator of said first group corresponding to the resonant frequency of the resonator of said second group, the resonant frequency of said secondary resonators of each of said groups corresponding to the resonant frequency of the primary resonator of said groups, means to generate an electron beam axially aligned with and arranged on the side of said first group of cavity resonator elements remote from said concentrator solenoid, focusing means interposed between said generator means and said side of said first group to traject said beam into the apertures of said groups of cavity resonator elements and means to collect electrons from said beam axially aligned and arranged at the end of said groups remote from said generator means.
